COLLAPSIBLE TUBE CLOSURE

Paul Martin Grafe, Livingston, N. J.

Application October 31, 1938, Serial No. 238,023

3 Claims. (Cl. 221—60)

The present invention relates to new and useful improvements in closures for containers, particularly collapsible tubes, and has for its primary object to provide, in a manner as hereininafter set forth, a device of this character which is adapted to be expeditiously mounted on the neck of the collapsible tube in lieu of the usual screw cap and which, after it has been so mounted, may be left thereon until all of the content has been used, after which the closure may be transferred to a full tube.

Another very important object of the invention is to provide a closure of the aforementioned character comprising a slidable valve of a novel construction and arrangement for controlling the discharge of the paste, cream or other material from the tube.

Other objects of the invention are to provide a collapsible tube closure of the character described which will be comparatively simple in construction, strong, durable, highly efficient and reliable in use, compact and which may be manufactured at low cost.

All of the foregoing and still further objects and advantages of the invention will become apparent from a study of the following specification, taken in connection with the accompanying drawing wherein like characters of reference designate corresponding parts throughout the several views, and wherein:

Figure 1 is a top plan view of a closure constructed in accordance with the present invention, showing same mounted on a collapsible tube.

Figure 2 is a view in side elevation thereof.

Figure 3 is an end elevational view.

Referring now to the drawing in detail, it will be seen that the embodiment of the invention which has been illustrated comprises a plate 1 of any suitable material, said plate being substantially rectangular in plan. While the lower face of the plate 1 is substantially flat, the top thereof is arcuate in cross section, as at 2.

The plate 1 has formed in the lower portion thereof a threaded socket 3 for the reception of the usual neck 4 of a collapsible tube 5. Thus, the plate 1 is removably mounted on the tube 5. Formed in the upper portion of the plate 1 is a discharge passage 6 which communicates with the socket 3 for receiving paste, cream, etc., from the collapsible tube 5.

Mounted for longitudinal movement on the top 2 of the plate 1 is a slidable valve 7 of arcuate cross section, said valve also being of any suitable material. The slidable valve 7 has formed

therein a port 8 for registry with the discharge passage 6 of the plate 1.

Projecting from the ends of the slidable valve 7 are integral discs constituting handles or the like 9 for actuating said slidable valve in opposite directions. Formed longitudinally in the end portions of the slidable valve 7 are slots 10. The slots 10 accommodate screws 11 which are mounted in the plate 1 and which slidably secure the valve 7 thereon.

It is thought that the manner in which the closure functions will be readily apparent from a consideration of the foregoing. With the valve 7 in the position shown to advantage in Fig. 1 of the drawing, the port 8 is out of registry with the discharge passage 6 and the collapsible tube 5 is closed. When it is desired to open the collapsible tube 5, the valve 7 is simply shifted longitudinally on the plate 1 in a manner to bring the port 8 into registry with the discharge passage 6. The construction and arrangement of the slots 10 and the screws 11 is such that the movement of the slidable valve 7 toward open position will be arrested when the port 8 is in full registry with the discharge passage 6. It will also be observed that the construction and arrangement is such that one of the handles 9 projects beyond the corresponding end of the plate 1 when the valve 7 is in either open or closed position. Thus, the user knows that the desired movement of the valve 7 may be had through the medium of the handle 9 which is projecting beyond or free of the plate 1.

It is believed that the many advantages of a collapsible tube closure constructed in accordance with the present invention will be readily understood although a preferred embodiment of the device is as illustrated and described, it is to be understood that changes in the details of construction and in the combination and arrangement of parts may be resorted to which will fall within the scope of the invention as claimed.

What is claimed is:

1. A closure of the class described comprising a plate adapted to be threadedly mounted on a container and having a discharge passage therein for communication with the container, said plate including a top of substantially arcuate cross section, a valve of substantially arcuate cross section slidably mounted on the plate and having a port therein for communication with the discharge passage, said valve further having slots therein, headed elements mounted on the plate and engaged in the slots for slidably securing the valve on the plate and for limiting

the movement of said valve in opposite directions on said plate, and integral operating handles projecting from opposite ends of the valve.

2. A closure of the class described comprising a substantially rectangular plate adapted to be mounted on a container and having a discharge passage therein for communication with the container, a valve slidably mounted on the plate and operable longitudinally thereon, said valve having a port therein for registry with the discharge passage in the plate, means for slidably securing the valve to the plate and for limiting the movement of said valve in opposite directions, and integral handles projecting from the ends of the valve and constituting means for operating same in opposite directions, the length of the valve and either one of the handles being substantially equal to the length of the plate.
3. A closure of the class described comprising a substantially rectangular plate having a thread-

ed socket in the lower portion thereof for removably mounting said plate on the neck of a container, said plate including a top of substantially arcuate cross section having a discharge passage therein communicating with the socket for receiving material from the container, a substantially rectangular valve of arcuate cross section mounted for longitudinal sliding movement on the plate, said valve having a port therein for registry with the discharge passage and further having longitudinal slots therein, screws threadedly mounted on the plate and engaged in the slots for slidably securing said valve and for limiting the movement thereof in opposite directions on the plate, and integral operating handles projecting longitudinally from the ends of the valve, the length of the valve and either of the handles corresponding to the length of the plate.
